United States Patent Office.

GAIUS L. PARKER, OF COVENTRYVILLE, NEW YORK.

Letters Patent No. 78,391, dated May 26, 1868.

IMPROVED BOILER FOR MAKING MAPLE-SUGAR.

The Schedule referred to in these Letters Patent and making part of the same.

TO ALL WHOM IT MAY CONCERN:

Be it known that I, GAIUS L. PARKER, of Coventryville, in the county of Chenango, and in the State of New York, have invented new and useful Improvements in Boilers for Making Maple-Sugar; and I do hereby declare that the following is a full, clear, and exact description thereof, reference being had to the accompanying drawings, and the letters of reference marked thereon.

In the annexed drawings, making a part of this specification—

Figure 1 represents a perspective,

Figure 2 represents a plan view, and

Figure 3 is an end view of my evaporator or boiler for making maple-sugar.

A represents a metallic plate, of suitable dimensions, bent in such manner and shape as to form an arch, the sides again bent upward, nearly parallel with the sides of the arch, and extending somewhat above the top of the said arch, in a vertical position.

B represent end pieces, of a shape to correspond with the space between the sides of the boiler and sides of the arch at its top, and which are fastened so as to make the boiler water-tight.

At one end there are holes, x x, at the bottom of the boiler, which is near the ground or base upon which it is designed to rest, for the purpose of affording a convenient device for letting off water whenever it may be necessary to empty the boiler, or to draw off sirup that may be made therein.

It will be seen that by this device there is a narrow space between the side of the boiler and the side of the arch which forms a part of the boiler.

This boiler may be placed on the ground where it may be desired to use it, or upon any suitable base, and the fire built beneath the arch thereof, both ends of which are open, and the sides and bottom both derive heat from the fire, and as the article or material to be heated is brought in contact with the sides as well as bottom of the heated surface, it follows that nearly or quite double the heat of the same fire is made available to what would be secured by the use of an ordinary boiler.

This boiler is, for convenience, provided with handles, C C, at each end.

Having thus fully described my invention, what I claim as new, and desire to secure by Letters Patent, is—

The cast-iron heads B B, with narrow flanges extending outwards, so that the sheet metal, A, may be bent or stamped, to conform to the shape of the heads, and thereto be riveted to the flanges, all constructed and used as specified.

In testimony that I claim the foregoing, I have hereunto set my hand, this 21st day of December, 1867.
